LIQUID EJECTING APPARATUS, DRIVE CIRCUIT, AND CIRCUIT SUBSTRATE

The present application is based on, and claims priority from JP Application Serial Number 2019-179176, filed Sep. 30, 2019, the disclosure of which is hereby incorporated by reference herein in its entirety.

BACKGROUND

1. Technical Field

The present disclosure relates to a liquid ejecting apparatus, a drive circuit, and a circuit substrate.

2. Related Art

There is known a liquid ejecting apparatus that uses a piezoelectric element such as a piezo element to print an image or a document on a medium by ejecting the ink as a liquid. The piezoelectric element is provided corresponding to each of the plurality of nozzles that ejects the ink onto the medium. When each piezoelectric element is driven according to the drive signal, a predetermined amount of ink is ejected from the corresponding nozzle at a predetermined timing, and the ejected ink lands on the medium, so that a dot is formed at a desired position on the medium.

Such a piezoelectric element is electrically a capacitive load, such as a capacitor, and therefore, it is necessary to supply a sufficient current to a plurality of piezoelectric elements to operate the piezoelectric elements corresponding to a plurality of nozzles. Therefore, in order to supply a sufficient current to the piezoelectric elements, the liquid ejecting apparatus includes a drive signal output circuit that includes an amplifier circuit that amplifies the supplied original signal to output it as a drive signal. The amplifier circuit included in such a drive signal output circuit, for example may include a class A amplifier circuit, a class B amplifier circuit, a class AB amplifier circuit, or the like, but from the viewpoint of power consumption reduction, in some cases, a class D amplifier circuit that is superior in energy conversion efficiency to the class A amplifier circuit, the class B amplifier circuit, and the class AB amplifier circuit is used.

Further, in response to the recent demand for further improvement in printing accuracy, the number of nozzles included in the liquid ejecting apparatus has increased, and as a result, the number of piezoelectric elements included in the liquid ejecting apparatus has also increased. Therefore, the amount of current output by the drive signal output circuit that drives the piezoelectric element is further increasing. A liquid ejecting apparatus including a plurality of drive signal output circuits is known to solve such a problem.

JP-A-2018-051821 discloses a liquid ejecting apparatus in which a plurality of circuit substrates on each of which the drive signal output circuit is mounted is included, and a plurality of circuit substrates and a relay substrate are electrically coupled to each other.

The drive signal output circuit amplifies an original signal having a small voltage value and a small current value to input, and outputs a drive signal having a large voltage value and a large current value. Therefore, as described in JP-A-2018-051821, the width of the output terminal through which the drive signal having a large current value is output is set wider than the width of the input terminal through which the original signal is input. For this reason, the drive

signal output circuit is required to include a plurality of types of terminals or connectors according to the input signal or the output signal. As a result, the circuit substrate on which the drive signal output circuit is mounted has a large area occupied by the input terminal and the output terminal, so that there is room for improvement in terms of downsizing of the circuit substrate.

SUMMARY

According to an aspect of the present disclosure, a liquid ejecting apparatus includes a print head including a drive element, where the print head ejects a liquid by driving the drive element, a first circuit substrate electrically coupled to the print head, a second circuit substrate electrically coupled to the first circuit substrate, and a first fixing portion that fixes the second circuit substrate to the first circuit substrate, wherein the first circuit substrate includes a coupling terminal electrically coupled to the print head, and a first substrate 10 on which the coupling terminal is provided, wherein the second circuit substrate includes a first drive signal output circuit that outputs a first drive signal for driving the drive element, an input terminal that is electrically coupled to the first circuit substrate, and through which a first base drive signal which is a basis of the first drive signal is input to the first drive signal output circuit, and a second substrate 15 on which the first drive signal output circuit and the input terminal are provided, and wherein the first fixing portion also serves as a first output terminal through which the first drive signal is output to the first circuit substrate.

According to another aspect of the present disclosure, in the liquid ejecting apparatus, the first drive signal output circuit may be located between the first fixing portion and the input terminal.

According to still another aspect of the present disclosure, in the liquid ejecting apparatus, when viewed from a direction orthogonal to one face of the first substrate, the first circuit substrate and the second circuit substrate may be disposed so that at least part of one face of the first substrate and one face of the second substrate overlap each other.

According to still another aspect of the present disclosure, the liquid ejecting apparatus may further include a reference voltage signal output circuit that outputs a reference voltage signal, and a second fixing portion that fixes the second circuit substrate to the first circuit substrate, wherein the drive element may be a piezoelectric element, and may be driven based on a first electrode to which the first drive signal is supplied and a second electrode to which the reference voltage signal is supplied, wherein the reference voltage signal output circuit may be provided on the second substrate, and wherein the second fixing portion may also serve as a second output terminal through which the reference voltage signal is output to the first circuit substrate.

According to still another aspect of the present disclosure, the liquid ejecting apparatus may further include a second drive signal output circuit that outputs a second drive signal for driving the drive element, and a third fixing portion that fixes the second circuit substrate to the first circuit substrate, wherein the second drive signal output circuit may be provided on the second substrate, wherein the third fixing portion may also serve as a third output terminal through which the second drive signal is output to the first circuit substrate, and wherein the second fixing portion may be located between the first fixing portion and the third fixing portion.

According to still another aspect of the present disclosure, a drive circuit includes a first circuit substrate, a second

circuit substrate electrically coupled to the first circuit substrate, and a first fixing portion that fixes the second circuit substrate to the first circuit substrate, wherein the second circuit substrate includes a first drive signal output circuit that outputs a first drive signal for driving a drive element, an input terminal that is electrically coupled to the first circuit substrate, and through which a first base drive signal which is a basis of the first drive signal is input to the first drive signal output circuit, and a second substrate on which the first drive signal output circuit and the input terminal are provided, and wherein the first fixing portion also serves as a first output terminal through which the first drive signal is output to the first circuit substrate.

According to still another aspect of the present disclosure, in a circuit substrate electrically coupled to a first substrate, the circuit substrate includes a first drive signal output circuit that outputs a first drive signal for driving a drive element, an input terminal that is electrically coupled to the first drive signal output circuit, and through which a first base drive signal which is a basis of the first drive signal is input to the first drive signal output circuit, a first fixing member mounting unit having a first fixing portion fixed to the first substrate, and a second substrate on which the first drive signal output circuit, the input terminal, and the first fixing member mounting unit are provided, wherein the first fixing member mounting unit also serves as a first output terminal through which the first drive signal is output.

BRIEF DESCRIPTION OF THE DRAWINGS

FIG. 1 is a diagram illustrating a schematic configuration of the inside of a liquid ejecting apparatus.

FIG. 2 is a diagram illustrating an electrical configuration of a liquid ejecting apparatus.

FIG. 3 is a diagram illustrating a schematic configuration of one of ejection units.

FIG. 4 is a diagram illustrating an example of waveforms of drive signals COMA and COMB.

FIG. 5 is a diagram illustrating an example of waveforms of a drive signal VOUT.

FIG. 6 is a diagram illustrating a configuration of a selection control circuit and a selection circuit.

FIG. 7 is a diagram illustrating the decoding contents in a decoder.

FIG. 8 is a diagram illustrating a configuration of a selection circuit corresponding to one ejection unit.

FIG. 9 is a diagram for explaining an operation of the selection control circuit and the selection circuit.

FIG. 10 is a diagram illustrating a circuit configuration of a drive signal output circuit.

FIG. 11 is a diagram illustrating the waveforms of a voltage signal As and a modulation signal Ms in association with the waveform of an analog base drive signal aA.

FIG. 12 is a plan view illustrating a configuration of a drive circuit substrate.

FIG. 13 is a plan view illustrating a configuration of a drive signal output circuit substrate.

FIG. 14 is a diagram illustrating a cross section taken along line XIV-XIV of FIG. 12.

FIG. 15 is a diagram illustrating a cross section taken along line XV-XV of FIG. 12.

FIG. 16 is a plan view illustrating a configuration of a drive circuit substrate according to a second embodiment.

FIG. 17 is a plan view illustrating a configuration of a drive signal output circuit substrate according to the second embodiment.

DESCRIPTION OF EXEMPLARY EMBODIMENTS

Hereinafter, preferred embodiments of the present disclosure will be described with reference to the drawings. The drawings used are for convenience of explanation. The embodiments described below do not unduly limit the details of the present disclosure described in the claims. In addition, all of the configurations described below are not necessarily essential components of the disclosure.

1. First Embodiment

1.1 Configuration of Liquid Ejecting Apparatus

FIG. 1 is a diagram illustrating a schematic configuration of the inside of a liquid ejecting apparatus 1 according to the first embodiment. The liquid ejecting apparatus 1 is an ink jet printer in which the ink as a liquid is ejected in accordance with image data supplied from a host computer provided outside to form dots on a medium P such as paper, thereby printing an image according to the supplied image data. In FIG. 1, some of the components of the liquid ejecting apparatus 1 such as a housing and a cover are not shown.

As shown in FIG. 1, the liquid ejecting apparatus 1 includes a movement mechanism 3 that moves a head unit 2 in the main scanning direction. The movement mechanism 3 includes a carriage motor 31 serving as the driving source of the head unit 2, a carriage guide shaft 32 having both ends fixed, a timing belt 33 extending substantially parallel to the carriage guide shaft 32 and driven by the carriage motor 31. The movement mechanism 3 includes a linear encoder 90 that detects the position of the head unit 2 in the main scanning direction.

A carriage 24 of the head unit 2 is configured so that a predetermined number of ink cartridges 22 can be mounted thereon. The carriage 24 is reciprocably supported by the carriage guide shaft 32 and is fixed to a portion of the timing belt 33. Accordingly, the carriage 24 of the head unit 2 is guided by the carriage guide shaft 32 and reciprocates when the carriage motor 31 causes the timing belt 33 to travel forward and backward. That is, the carriage motor 31 moves the carriage 24 in the main scanning direction. A print head 20 is attached to a portion of the carriage 24, facing the medium P. As will be described later, the print head 20 includes a large number of nozzles, and ejects a predetermined amount of the ink from each nozzle at a predetermined timing. Various control signals are supplied to the head unit 2 operating as described above via a flexible flat cable 190.

The liquid ejecting apparatus 1 includes a transport mechanism 4 that transports the medium P in the sub scanning direction. The transport mechanism 4 includes a platen 43 that supports the medium P, a transport motor 41 that is a driving source, and a transport roller 42 that is rotated by the transport motor 41 and transports the medium P in the sub scanning direction. In a state where the medium P is supported by the platen 43, the ink is ejected from the print head 20 onto the medium P according to the timing at which the medium P is transported by the transport mechanism 4, so that a desired image is formed on the surface of the medium P.

A home position serving as a base point of the head unit 2 is set in an end region within the movement range of the carriage 24 included in the head unit 2. A capping member 70 that seals the nozzle formation face of the print head 20 and a wiper member 71 that wipes the nozzle formation face

are disposed at the home position. The liquid ejecting apparatus **1** forms an image on the surface of the medium **P** bidirectionally when the carriage **24** moves forward toward the end opposite the home position, and when the carriage **24** moves backward from the opposite end toward the home position.

A flushing box **72** that collects the ink ejected from the print head **20** during a flushing operation is provided at the end of the platen **43** in the main scanning direction, and at the end opposite the home position from which the carriage **24** moves. The flushing operation is an operation of forcibly ejecting the ink from each nozzle regardless of the image data in order to prevent the possibility that the proper amount of the ink will not be ejected due to the nozzle clogging because of thickening of the ink near the nozzle, the air bubbles mixed in the nozzle, and the like. Note that the flushing boxes **72** may be provided on both sides of the platen **43** in the main scanning direction.

1.2 Electrical Configuration of Liquid Ejecting Apparatus

FIG. 2 is a diagram illustrating an electrical configuration of the liquid ejecting apparatus **1**. As shown in FIG. 2, the liquid ejecting apparatus **1** includes a control unit **10** and the head unit **2**. The control unit **10** and the head unit **2** are electrically coupled to each other via the flexible flat cable **190**.

The control unit **10** includes a control circuit **100**, a carriage motor driver **35**, and a transport motor driver **45**. The control circuit **100** generates a control signal corresponding to the image data supplied from the host computer to output the generated control signal to a corresponding configuration.

Specifically, the control circuit **100** grasps the current scanning position of the head unit **2** based on the detection signal of the linear encoder **90**. The control circuit **100** generates control signals **CTR1** and **CTR2** corresponding to the current scanning position of the head unit **2**. The control signal **CTR1** is supplied to the carriage motor driver **35**. The carriage motor driver **35** drives the carriage motor **31** according to the input control signal **CTR1**. Further, the control signal **CTR2** is supplied to the transport motor driver **45**. The transport motor driver **45** drives the transport motor **41** according to the input control signal **CTR2**. As a result, the movement of the carriage **24** in the main scanning direction and the transport of the medium **P** in the sub scanning direction are controlled.

In addition, the control circuit **100** generates, based on image data supplied from an externally provided host computer and a detection signal of the linear encoder **90**, a clock signal **SCK**, a print data signal **SI**, a latch signal **LAT**, a change signal **CH**, and base drive signals **dA** and **dB** corresponding to the current scanning position of the head unit **2** to output the generated signals to head unit **2**.

Further, the control circuit **100** causes a maintenance unit **80** to perform a maintenance process of restoring the ink ejection state of an ejection unit **600** to a normal state. The maintenance unit **80** includes a cleaning mechanism **81** and a wiping mechanism **82**. The cleaning mechanism **81** performs, as a maintenance process, a pumping process of sucking the thickened ink, the air bubbles, and the like that are stored in the ejection unit **600** by a tube pump (not shown). Further, the wiping mechanism **82** performs, as a maintenance process, a wiping process of wiping foreign matter such as paper dust attached to the vicinity of the nozzle of the ejection unit **600** with the wiper member **71**. The control circuit **100** may perform the above-described flushing operation as a maintenance process of restoring the ink ejection state of the ejection unit **600** to a normal state.

The head unit **2** includes a drive circuit **50** and the print head **20**.

The drive circuit **50** includes drive signal output circuits **51a** and **51b**. The digital base drive signal **dA** is input to the drive signal output circuit **51a**. The drive signal output circuit **51a** generates a drive signal **COMA** by digital-to-analog converting the input base drive signal **dA** to class-D amplify the converted analog signal to output the generated drive signal **COMA** to the print head **20**. Similarly, the digital base drive signal **dB** is input to the drive signal output circuit **51b**. The drive signal output circuit **51b** generates a drive signal **COMB** by digital-to-analog converting the input base drive signal **dB** to class-D amplify the converted analog signal to output the generated drive signal **COMB** to the print head **20**.

That is, the base drive signal **dA** defines the waveform of the drive signal **COMA**, and the base drive signal **dB** defines the waveform of the drive signal **COMB**. Therefore, the base drive signals **dA** and **dB** may be signals that can define the waveforms of the drive signals **COMA** and **COMB**, and may be analog signals, for example. The details of the drive signal output circuits **51a** and **51b** will be described later. Further, in the description of FIG. 2, the drive circuit **50** is described as being included in the head unit **2**, but the drive circuit **50** may be included in the control unit **10**. In this case, the drive signals **COMA** and **COMB** output from the drive signal output circuits **51a** and **51b** are supplied to the print head **20** via the flexible flat cable **190**.

The print head **20** includes a selection control circuit **210**, a plurality of selection circuits **230**, and a plurality of ejection units **600** corresponding to the plurality of respective selection circuits **230**. The selection control circuit **210** generates, based on the clock signal **SCK**, the print data signal **SI**, the latch signal **LAT**, and the change signal **CH** supplied from the control circuit **100**, a selection signal for selecting or deselecting the waveforms of the drive signals **COMA** and **COMB** to output the generated selection signal to each of the plurality of selection circuits **230**.

The drive signals **COMA** and **COMB** and the selection signal output from the selection control circuit **210** are input to each selection circuit **230**. By selecting or deselecting the waveforms of the drive signals **COMA** and **COMB** based on the input selection signal, the selection circuit **230** generates a drive signal **VOUT** based on the drive signals **COMA** and **COMB** to output the generated drive signal **VOUT** to the corresponding ejection unit **600**.

Each ejection unit **600** includes a piezoelectric element **60**. The drive signal **VOUT** output from the corresponding selection circuit **230** is supplied to one end of the piezoelectric element **60**. Further, a reference voltage signal **VBS** is supplied to the other end of the piezoelectric element **60**. The piezoelectric element **60** included in the ejection unit **600** is driven according to a potential difference between the drive signal **VOUT** supplied to the one end and the reference voltage signal **VBS** supplied to the other end. An amount of the ink corresponding to the driving of the piezoelectric element **60** is ejected from the ejection unit **600**.

Here, the drive signal **COMA** which is the basis of the drive signal **VOUT** for driving the piezoelectric element **60** is an example of a first drive signal, and the drive signal output circuit **51a** that outputs the drive signal **COMA** is an example of a first drive signal output circuit. Further, the drive signal **COMB** that is the basis of the drive signal **VOUT** for driving the piezoelectric element **60** is another example of the first drive signal, and the drive signal output circuit **51b** that outputs the drive signal **COMB** is another example of the first drive signal output circuit. The drive

signal VOUT is generated by selecting or deselecting the waveforms of the drive signals COMA and COMB. Therefore, the drive signal VOUT is also an example of the first drive signal. The piezoelectric element 60 that is driven by the drive signal VOUT being supplied is an example of the drive element, and the print head 20 that includes the piezoelectric element 60, and that ejects a liquid by driving the piezoelectric element 60 is an example of the print head. 1.3 Configuration of Ejection Unit

FIG. 3 is a diagram illustrating a schematic configuration of one of the plurality of ejection units 600 included in the print head 20. As shown in FIG. 3, the ejection unit 600 includes the piezoelectric element 60, a vibration plate 621, a cavity 631, and a nozzle 651.

The cavity 631 is filled with the ink supplied from a reservoir 641. Further, the ink is introduced into the reservoir 641 from the ink cartridge 22 via an ink tube (not shown) and a supply port 661. That is, the cavity 631 is filled with the ink stored in the corresponding ink cartridge 22.

The vibration plate 621 is displaced by driving the piezoelectric element 60 provided on the upper face in FIG. 3. With the displacement of the vibration plate 621, the internal volume of the cavity 631 filled with the ink expands or contracts. That is, the vibration plate 621 functions as a diaphragm that changes the internal volume of the cavity 631.

The nozzle 651 is an opening provided in a nozzle plate 632 and communicating with the cavity 631. When the internal volume of the cavity 631 changes, an amount of the ink corresponding to the change in the internal volume is ejected from the nozzle 651.

The piezoelectric element 60 has a structure in which a piezoelectric body 601 is sandwiched between a pair of electrodes 611 and 612. In the piezoelectric body 601 having such a structure, the central portion of the electrodes 611 and 612 bends in the vertical direction together with the vibration plate 621 according to the potential difference between the voltages applied by the electrodes 611 and 612. Specifically, the drive signal VOUT is supplied to the electrode 611 of the piezoelectric element 60. Further, the reference voltage signal VBS is supplied to the electrode 612 of the piezoelectric element 60. The piezoelectric element 60 bends upward when the voltage level of the drive signal VOUT increases, and bends downward when the voltage level of the drive signal VOUT decreases.

In the ejection unit 600 configured as described above, the vibration plate 621 is displaced by the piezoelectric element 60 bending upward to increase the internal volume of the cavity 631. As a result, the ink is drawn from the reservoir 641. On the other hand, when the piezoelectric element 60 bends downward, the vibration plate 621 is displaced to reduce the internal volume of the cavity 631. As a result, an amount of the ink corresponding to the degree of reduction is ejected from the nozzle 651.

Here, the electrode 611 supplied with the drive signal VOUT is an example of the first electrode, and the electrode 612 supplied with the reference voltage signal VBS is an example of the second electrode. The piezoelectric element 60 is driven based on the electrode 611 supplied with the drive signal VOUT and the electrode 612 supplied with the reference voltage signal VBS. The piezoelectric element 60 is not limited to the structure shown in FIG. 3, but may have any structure as long as it can eject the ink from the ejection unit 600. Therefore, the piezoelectric element 60 is not limited to the above-described configuration of the bending vibration, but may be, for example, a configuration using the longitudinal vibration.

1.4 Configuration and Operation of Print Head

Next, the configuration and operation of the print head 20 will be described. As described above, the print head 20 generates the drive signal VOUT by selecting or deselecting the drive signals COMA and COMB output from the drive circuit 50 based on the clock signal SCK, the print data signal SI, the latch signal LAT, and the change signal CH to supply the generated drive signal VOUT to the corresponding ejection unit 600. Therefore, in describing the configuration and operation of the print head 20, first, an example of the waveforms of the drive signals COMA and COMB and an example of the waveform of the drive signal VOUT will be described.

FIG. 4 is a diagram illustrating an example of the waveforms of the drive signals COMA and COMB. As shown in FIG. 4, the drive signal COMA includes a waveform in which a trapezoidal waveform Adp1 disposed in a period T1 from the rise of the latch signal LAT to the rise of the change signal CH, and a trapezoidal waveform Adp2 disposed in a period T2 from the rise of the change signal CH to the rise of the latch signal LAT are continuous. The trapezoidal waveform Adp1 is a waveform for ejecting a small amount of the ink from the nozzle 651, and the trapezoidal waveform Adp2 is a waveform for ejecting a medium amount of the ink that is larger than the small amount of the ink from the nozzle 651.

Further, the drive signal COMB includes a waveform in which a trapezoidal waveform Bdp1 disposed in the period T1 and a trapezoidal waveform Bdp2 disposed in the period T2 are continuous. The trapezoidal waveform Bdp1 is a waveform for not ejecting the ink from the nozzle 651, and is a waveform for preventing an increase in the ink viscosity by vibrating the ink near the opening of the nozzle 651. Further, as in the trapezoidal waveform Adp1, the trapezoidal waveform Bdp2 is a waveform for ejecting a small amount of the ink from the nozzles 651.

The voltages at the start timing and the end timing of each of the trapezoidal waveforms Adp1, Adp2, Bdp1, and Bdp2 are commonly a voltage Vc. That is, each of the trapezoidal waveforms Adp1, Adp2, Bdp1, and Bdp2 is a waveform that starts at the voltage Vc and ends at the voltage Vc. A cycle Ta including the period T1 and the period T2 corresponds to a printing cycle in which a new dot is formed on the medium P.

Here, in FIG. 4, the trapezoidal waveform Adp1 and the trapezoidal waveform Bdp2 are identical, but the trapezoidal waveform Adp1 and the trapezoidal waveform Bdp2 may be different. Further, the description is made assuming that a small amount of the ink is ejected from the corresponding nozzle when the trapezoidal waveform Adp1 is supplied to the ejection unit 600, and when the trapezoidal waveform Bdp1 is supplied to the ejection unit 600, but different amounts of the ink may be ejected. That is, the waveforms of the drive signals COMA and COMB are not limited to the waveforms shown in FIG. 4, but various waveforms may be combined depending on the moving speed of the carriage 24 to which the print head 20 is attached, the nature of the ink stored in the ink cartridge 22, the material of the medium P, and the like.

FIG. 5 is a diagram illustrating an example of the waveform of the drive signal VOUT. FIG. 5 shows the waveforms of the drive signal VOUT with the dots formed on the medium P having the sizes of the “large dot”, the “medium dot”, and the “small dot”, and “no dots recorded” in comparison.

As shown in FIG. 5, the drive signal VOUT when the “large dot” are formed on the medium P represents a

waveform in the cycle Ta in which the trapezoidal waveform Adp1 disposed in the period T1, and the trapezoidal waveform Adp2 disposed in the period T2 are continuous. When the drive signal VOUT is supplied to the ejection unit 600, a small amount of the ink and a medium amount of the ink are ejected from the corresponding nozzle 651 in the cycle Ta. Therefore, the large dot is formed on the medium P by landing and uniting the respective amounts of the ink.

The drive signal VOUT when the “medium dot” is formed on the medium P represents a waveform in the cycle Ta in which the trapezoidal waveform Adp1 disposed in the period T1, and the trapezoidal waveform Bdp2 disposed in the period T2 are continuous. When the drive signal VOUT is supplied to the ejection unit 600, a small amount of the ink is ejected twice from the corresponding nozzle 651 in the cycle Ta. Therefore, the medium dot is formed on the medium P by landing and uniting the respective amounts of the ink.

The drive signal VOUT when the “small dot” is formed on the medium P represents a waveform in the cycle Ta in which the trapezoidal waveform Adp1 disposed in the period T1, and a constant waveform, with the voltage Vc, disposed in the period T2 are continuous. When the drive signal VOUT is supplied to the ejection unit 600, a small amount of the ink is ejected from the corresponding nozzle 651 in the cycle Ta. Therefore, this amount of the ink lands on the medium P to form the small dot.

The drive signal VOUT corresponding to the “no dots recorded” in which no dots are formed on the medium P represents a waveform in the cycle Ta in which the trapezoidal waveform Bdp1 disposed in period T1, and a constant waveform, with the voltage Vc, disposed in the period T2 are continuous. When the drive signal VOUT is supplied to the ejection unit 600, the ink near the opening of the corresponding nozzle 651 only slightly vibrates, and no ink is ejected in the cycle Ta. Therefore, the ink does not land on the medium P and no dots are formed.

Here, the waveform that is constant at the voltage Vc is a waveform with a voltage of the immediately preceding voltage Vc being held in the piezoelectric element 60, which is a capacitive load, when none of the trapezoidal waveforms Adp1, Adp2, Bdp1, and Bdp2 is selected as the drive signal VOUT. Therefore, when none of the trapezoidal waveforms Adp1, Adp2, Bdp1, and Bdp2 is selected as the drive signal VOUT, it can be said that the voltage Vc is supplied to the ejection unit 600 as the drive signal VOUT.

The drive signal VOUT as described above is generated when the waveforms of the drive signals COMA and COMB are selected or deselected by the operation of the selection control circuit 210 and the selection circuit 230.

FIG. 6 is a diagram illustrating configurations of the selection control circuit 210 and the selection circuits 230. As shown in FIG. 6, the print data signal SI, the latch signal LAT, the change signal CH, and the clock signal SCK are input to the selection control circuit 210. The selection control circuit 210 includes a set of a shift register (S/R) 212, a latch circuit 214, and a decoder 216 corresponding to each of the m ejection units 600. That is, the selection control circuit 210 includes the same number of sets of the shift registers 212, the latch circuits 214, and the decoders 216 as the m ejection units 600.

The print data signal SI is a signal synchronized with the clock signal SCK, and is a total 2-m-bit signal including 2-bit print data [SIH, SIL] for selecting any one of the “large dot”, the “medium dot”, the “small dot”, and the “no dots recorded” for each of the m ejection units 600. The input print data signal SI is held in the shift register 212 for 2-bit

print data [SIH, SIL] included in the print data signal SI corresponding to each of the m ejection units 600. Specifically, the selection control circuit 210 is configured such that the m-stage shift registers 212 corresponding to the m ejection units 600 are cascade-coupled to each other, and the print data signal SI input serially is sequentially transferred to the subsequent stage according to the clock signal SCK. In FIG. 6, in order to distinguish the shift registers 212, they are denoted as the first stage, the second stage . . . the m-th stage in order from the upstream shift register to which the print data signal SI is input.

Each of the m latch circuits 214 latches the 2-bit print data [SIH, SIL] held by the respective m shift registers 212 at the rising edge of the latch signal LAT.

FIG. 7 is a diagram illustrating the decoding contents in the decoder 216. The decoder 216 outputs selection signals S1 and S2 according to the 2-bit print data [SIH, SIL] latched by the latch circuit 214. For example, when the 2-bit print data [SIH, SIL] is [1, 0], the decoder 216 outputs the logic level of the selection signal S1 as H and L levels in the periods T1 and T2, and the logic level of the selection signal S2 as L and H levels in the periods T1 and T2 to the selection circuit 230.

The selection circuit 230 is provided corresponding to each of the ejection units 600. That is, the number of the selection circuits 230 included in the print head 20 is m, which is the same as the total number of the ejection units 600. FIG. 8 is a diagram illustrating a configuration of the selection circuit 230 corresponding to one ejection unit 600. As shown in FIG. 8, the selection circuit 230 includes inverters 232a and 232b, which are NOT circuits, and transfer gates 234a and 234b.

The selection signal S1 is input to the non-circled positive control terminal in the transfer gate 234a, while being input to the circled negative control terminal in the transfer gate 234a after logically inverted by the inverter 232a. The drive signal COMA is supplied to the input end of the transfer gate 234a. The selection signal S2 is input to the non-circled positive control terminal in the transfer gate 234b, while being input to the circled negative control terminal in the transfer gate 234b after logically inverted by the inverter 232b. The drive signal COMB is supplied to the input end of the transfer gate 234b. The output ends of the transfer gates 234a and 234b are coupled in common and the drive signal COMA and the drive signal COMB are output as the drive signal VOUT.

Specifically, when the selection signal S1 is at H level, the transfer gate 234a is brought into a conductive state between the input end and the output end, and when the selection signal S1 is at L level, the transfer gate 234a is brought into a non-conductive state between the input end and the output end. When the selection signal S2 is at H level, the transfer gate 234b is brought into a conductive state between the input end and the output end, and when the selection signal S2 is at L level, the transfer gate 234b is brought into a non-conductive state between the input end and the output end. As described above, the selection circuit 230 generates and output the drive signal VOUT by selecting the waveforms of the drive signals COMA and COMB based on the selection signals S1 and S2.

Here, operations of the selection control circuit 210 and the selection circuit 230 will be described with reference to FIG. 9. FIG. 9 is a diagram for explaining the operations of the selection control circuit 210 and the selection circuit 230. The print data signal SI is serially input in synchronization with the clock signal SCK, and is sequentially transferred to the shift registers 212 corresponding to the respective ejec-

tion units **600**. When the input of the clock signal SCK stops, each shift register **212** holds 2-bit print data [SIH, SIL] corresponding to each of the ejection units **600**. The print data signal SI is input to the shift registers **212** of the m-th stage . . . the second stage, the first-stage in the order of the corresponding ejection units **600**.

When the latch signal LAT rises, each of the latch circuits **214** simultaneously latches the 2-bit print data [SIH, SIL] held in the respective shift registers **212**. In FIG. 9, LT₁, LT₂ . . . LT_m indicate 2-bit print data [SIH, SIL] latched by the latch circuits **214** corresponding to the shift registers **212** of the first stage, the second stage . . . the m-th stage, respectively.

The decoder **216** outputs the logic levels of the selection signals S₁ and S₂ according to the contents as shown in FIG. 7 in each of the periods T₁ and T₂ according to a dot size defined by the latched 2-bit print data [SIH, SIL].

Specifically, when the print data [SIH, SIL] is [1, 1], the decoder **216** sets the selection signal S₁ to H and H levels in the periods T₁ and T₂, and sets the selection signal S₂ to L and L levels in the periods T₁ and T₂. In this case, the selection circuit **230** selects the trapezoidal waveform Adp₁ in the period T₁, and selects the trapezoidal waveform Adp₂ in the period T₂. As a result, the drive signal V_{OUT} corresponding to the “large dot” shown in FIG. 5 is generated.

Also, when the print data [SIH, SIL] is [1, 0], the decoder **216** sets the selection signal S₁ to H and L levels in the periods T₁ and T₂, and sets the selection signal S₂ to L and H levels in the periods T₁ and T₂. In this case, the selection circuit **230** selects the trapezoidal waveform Adp₁ in the period T₁, and selects the trapezoidal waveform Bdp₂ in the period T₂. As a result, the drive signal V_{OUT} corresponding to the “medium dot” shown in FIG. 5 is generated.

Further, when the print data [SIH, SIL] is [0, 1], the decoder **216** sets the selection signal S₁ to H and L levels in the periods T₁ and T₂, and sets the selection signal S₂ to L and L levels in the periods T₁ and T₂. In this case, the selection circuit **230** selects the trapezoidal waveform Adp₁ in the period T₁, and selects none of the trapezoidal waveforms Adp₂ and Bdp₂ in the period T₂. As a result, the drive signal V_{OUT} corresponding to the “small dot” shown in FIG. 5 is generated.

Further, when the print data [SIH, SIL] is [0, 0], the decoder **216** sets the selection signal S₁ to L and L levels in the periods T₁ and T₂, and sets the selection signal S₂ to H and L levels in the periods T₁ and T₂. In this case, the selection circuit **230** selects the trapezoidal waveform Bdp₁ in the period T₁, and selects none of the trapezoidal waveforms Adp₂ and Bdp₂ in the period T₂. As a result, the drive signal V_{OUT} corresponding to “no dots recorded” shown in FIG. 5 is generated.

As mentioned above, the selection control circuit **210** and the select ion circuit **230** select the waveforms of the drive signals COMA and COMB based on the print data signal SI, the latch signal LAT, the change signal CH, and the clock signal SCK to output the selected waveforms as the drive signal V_{OUT} to the ejection unit **600**.

1.5 Configuration of Drive Signal Output Circuit

Next, the configuration and operation of the drive signal output circuits **51a** and **51b** that output the drive signals COMA and COMB will be described. Here, the drive signal output circuit **51a** and the drive signal output circuit **51b** have the same configuration except that the input signal and the output signal are different. Therefore, in the following description, only the configuration and operation of the drive signal output circuit **51a** will be described, and the descrip-

tion of the configuration and operation of the drive signal output circuit **51b** will be omitted.

The drive signal output circuit **51a** first converts the base drive signal dA into an analog signal, and second, feeds back the output drive signal COMA, and corrects the deviation between the attenuation signal based on the drive signal COMA and the target signal by a high-frequency component of the drive signal COMA to generate a modulation signal according to the corrected signal. Third, the drive signal output circuit **51a** generates an amplified modulation signal by switching transistors M₁ and M₂ according to the modulation signal, and fourth, demodulates the amplified modulation signal by smoothing the amplified modulation signal with a low-pass filter to output the demodulated signal as the drive signal COMA.

FIG. 10 is a diagram illustrating a circuit configuration of the drive signal output circuit **51a**. As shown in FIG. 10, the drive signal output circuit **51a** includes an integrated circuit **500** including a modulation circuit **510** that modulates the base drive signal dA input from the control circuit **100**, and that outputs a modulation signal Ms, and an output circuit **580** that amplifies the modulation signal Ms, and that outputs the drive signal COMA for driving the piezoelectric element **60** by demodulating.

Specifically, the drive signal output circuit **51a** includes the integrated circuit **500**, the output circuit **580**, a first feedback circuit **570**, a second feedback circuit **572**, and a plurality of other circuit elements.

The integrated circuit **500** is electrically coupled to the outside of the integrated circuit **500** through a plurality of terminals including a terminal In, a terminal Bst, a terminal Hdr, a terminal Sw, a terminal Gvd, a terminal Ldr, a terminal Gnd, and a terminal Vbs. The integrated circuit **500** modulates the base drive signal dA input from the terminal In to output an amplification control signal for driving each of the transistors M₁ and M₂ included in an amplifier circuit **550** included in the output circuit **580**.

As shown in FIG. 10, the integrated circuit **500** includes a digital to analog converter (DAC) **511**, the modulation circuit **510**, a gate drive circuit **520**, a reference voltage generation circuit **530**, and a power supply circuit **590**.

The power supply circuit **590** generates a first voltage signal DAC_HV and a second voltage signal DAC_LV to supply them to the DAC **511**.

The DAC **511** converts the digital base drive signal dA that defines the waveform of the drive signal COMA into the base drive signal aA that is an analog signal having a voltage value between the first voltage signal DAC_HV and the second voltage signal DAC_LV to output the converted base drive signal aA to the modulation circuit **510**. Note that the maximum value of the voltage amplitude of the base drive signal aA is defined by the first voltage signal DAC_HV, and the minimum value is defined by the second voltage signal DAC_LV. That is, the first voltage signal DAC_HV is a reference voltage of the DAC **511** on the high voltage side, and the second voltage signal DAC_LV is a reference voltage of the DAC **511** on the low voltage side. A signal obtained by amplifying the analog base drive signal aA is the drive signal COMA. That is, the base drive signal aA corresponds to a target signal before the amplification of the drive signal COMA. The voltage amplitude of the base drive signal aA in the present embodiment is, for example, 1 V to 2 V.

The modulation circuit **510** generates the modulation signal Ms obtained by modulating the base drive signal aA to output the generated modulation signal Ms to the amplifier circuit **550** via the gate drive circuit **520**. Modulation

circuit 510 includes adders 512 and 513, a comparator 514, an inverter 515, an integral attenuator 516, and an attenuator 517.

The integral attenuator 516 attenuates and integrates the voltage of a terminal Out input via a terminal Vfb, that is, the drive signal COMA, and supplies the attenuated and integrated signal to a negative input end of the adder 512. The base drive signal aA is input to a positive input end of the adder 512. The adder 512 supplies a voltage obtained by subtracting and integrating the voltage input to the negative input end from the voltage input to the positive input end to the positive input end of the adder 513.

Here, the maximum value of the voltage amplitude of the base drive signal aA is about 2 V as described above, whereas the maximum value of the voltage of the drive signal COMA may exceed 40 V in some cases. For this reason, the integral attenuator 516 attenuates the voltage of the drive signal COMA input via the terminal Vfb in order to match the amplitude ranges of both voltages when obtaining the deviation.

The attenuator 517 supplies a voltage obtained by attenuating the high-frequency component of the drive signal COMA input via a terminal Ifb to the negative input end of the adder 513. Further, the voltage output from the adder 512 is input to the positive input end of the adder 513. The adder 513 outputs to the comparator 514 the voltage signal As obtained by subtracting the voltage input to the negative input end from the voltage input to the positive input end.

The voltage signal As output from the adder 513 is a voltage obtained by subtracting the voltage of the signal supplied to the terminal Vfb and further subtracting the voltage of the signal supplied to the terminal Ifb from the voltage of the base drive signal aA. For this reason, the voltage of the voltage signal As output from the adder 513 is a signal obtained by correcting the deviation obtained by subtracting the attenuation voltage of the drive signal COMA from the target voltage of the base drive signal aA by the high-frequency component of the drive signal COMA.

The comparator 514 outputs the pulse-modulated modulation signal Ms based on the voltage signal As output from the adder 513. Specifically, the comparator 514 outputs the modulation signal Ms which is at H level when the voltage signal As output from the adder 513 is equal to or higher than a threshold Vth1 described later in a case where the voltage is rising, and is at L level when the voltage signal As falls below a threshold Vth2 described later in a case where the voltage is dropping. Here, the thresholds Vth1 and Vth2 are set in a relationship in which the threshold Vth1 is greater than the threshold Vth2. The frequency and the duty ratio of the modulation signal Ms change in accordance with the base drive signals dA and aA. Therefore, the attenuator 517 adjusts the modulation gain corresponding to the sensitivity, so that the change amount of the frequency or the duty ratio of the modulation signal Ms can be adjusted.

The modulation signal Ms output from the comparator 514 is supplied to a gate driver 521 included in the gate drive circuit 520. The modulation signal Ms is also supplied to a gate driver 522 included in the gate drive circuit 520 after the logic level is inverted by the inverter 515. That is, the logic levels of the signals supplied to the gate driver 521 and the gate driver 522 are mutually exclusive.

Here, the timing may be controlled so that the logic levels of the signals supplied to the gate driver 521 and the gate driver 522 are not H level at the same time. In other words, “exclusive” here means that the logic levels of the signals supplied to the gate driver 521 and the gate driver 522 are

not H level at the same time. For details, this means that the transistor M1 and the transistor M2 included in the amplifier circuit 550 are not turned on at the same time.

The modulation signal is, in a narrow sense, the modulation signal Ms, but assuming that the signal is pulse-modulated according to the analog base drive signal aA based on the digital base drive signal dA, a signal in which the logical level of the modulation signal Ms is inverted is also included in the modulation signal. That is, the modulation signal output from the modulation circuit 510 includes not only the modulation signal Ms input to the gate driver 521, but also a signal in which the logic level of the modulation signal Ms input to the gate driver 522 is inverted, and a signal whose timing is controlled with respect to the modulation signal Ms.

The gate drive circuit 520 includes the gate driver 521 and the gate driver 522.

The gate driver 521 shifts the level of the modulation signal Ms output from the comparator 514 to output the level-shifted modulation signal Ms as a first amplification control signal from the terminal Hdr. The higher side of the power supply voltage of the gate driver 521 is a voltage applied via the terminal Bst, and the lower side is a voltage applied via the terminal Sw. The terminal Bst is coupled to one end of a capacitor C5 and the cathode of a diode D1 for backflow prevention. The terminal Sw is coupled to the other end of the capacitor C5. The anode of the diode D1 is coupled to the terminal Gvd. As a result, a voltage Vm which is a DC voltage of, for example, 7.5 V supplied from a power supply circuit (not shown) is supplied to the anode of the diode D1. Therefore, the potential difference between the terminal Bst and the terminal Sw is approximately equal to the potential difference between both ends of the capacitor C5, that is, the voltage Vm. The gate driver 521 outputs, from the terminal Hdr, the first amplification control signal having a voltage higher than, by the voltage Vm, that of the terminal Sw according to the input modulation signal Ms.

The gate driver 522 operates at a lower potential than the gate driver 521. The gate driver 522 shifts the level of the signal obtained by inverting, by the inverter 515, the logical level of the modulation signal Ms output from the comparator 514 to output the level-shifted signal from the terminal Ldr as a second amplification control signal. The voltage Vm is applied to the higher side of the power supply voltage of the gate driver 522, and the ground potential of, for example, 0 V is supplied to the lower side via the terminal Gnd. The second amplification control signal having a voltage higher than, by the voltage Vm, that of the terminal Gnd according to the signal input to the gate driver 522 is output from the terminal Ldr.

The reference voltage generation circuit 530 outputs the reference voltage signal VBS of a DC voltage of, for example, 6 V, which is supplied to the electrode 612 of the piezoelectric element 60. The reference voltage generation circuit 530 is configured by a constant voltage circuit including a band gap reference circuit, for example. The reference voltage signal VBS is a signal of a potential serving as a reference for driving the piezoelectric element 60, and may be, for example, a signal of a ground potential. Here, the reference voltage generation circuit 530 that outputs the reference voltage signal VBS is an example of the reference voltage signal output circuit.

The output circuit 580 includes the amplifier circuit 550 and a smoothing circuit 560. The amplifier circuit 550 includes the transistor M1 and the transistor M2. The drain of the transistor M1 is electrically coupled to a terminal Hd of an accommodation unit 551. A voltage VHV, which is a

DC voltage of, for example, 42 V is supplied to the drain of the transistor M1. The gate of the transistor M1 is electrically coupled to one end of a resistor R1, and the other end of the resistor R1 is electrically coupled to the terminal Hdr of the integrated circuit 500. That is, the first amplification control signal output from the terminal Hdr of the integrated circuit 500 is supplied to the gate of the transistor M1. The source of the transistor M1 is electrically coupled to the terminal Sw of the integrated circuit 500.

The drain of the transistor M2 is electrically coupled to the terminal Sw of the integrated circuit 500. That is, the drain of the transistor M2 and the source of the transistor M1 are electrically coupled to each other. The gate of the transistor M2 is electrically coupled to one end of a resistor R2, and the other end of the resistor R2 is electrically coupled to the terminal Ldr of the integrated circuit 500. That is, the second amplification control signal output from the terminal Ldr of the integrated circuit 500 is supplied to the gate of the transistor M2. The ground potential is supplied to the source of the transistor M2.

In the amplifier circuit 550 configured as described above, when the transistor M1 is turned off and the transistor M2 is turned on, the voltage of the node to which the terminal Sw is coupled is the ground potential. Therefore, the voltage Vm is supplied to the terminal Bst. On the other hand, when the transistor M1 is turned on and the transistor M2 is turned off, the voltage of the node to which the terminal Sw is coupled is the voltage VHV. Therefore, a voltage signal of the potential of the voltage VHV+Vm is supplied to the terminal Bst.

That is, the gate driver 521 that drives the transistor M1 uses the capacitor C5 as a floating power supply, and when the potential of the terminal Sw changes to 0 V or the voltage VHV according to the operation of the transistor M1 and the transistor M2, supplies, to the gate of the transistor M1, the first amplification control signal whose L level is the potential of the voltage VHV and whose H level is the potential of the voltage VHV+the voltage Vm.

On the other hand, the gate driver 522 that drives the transistor M2 supplies, to the gate of the transistor M2, the second amplification control signal whose L level is the ground potential and whose H level is the potential of the voltage Vm irrespective of the operations of the transistor M1 and the transistor M2.

As described above, the amplifier circuit 550 amplifies, by the transistor M1 and the transistor M2, the modulation signal Ms obtained by modulating the base drive signals dA and aA. As a result, an amplified modulation signal is generated at the coupling point where the source of the transistor M1 and the drain of the transistor M2 are commonly coupled. Then, the amplified modulation signal generated by the amplifier circuit 550 is input to the smoothing circuit 560.

The smoothing circuit 560 generates the drive signal COMA by smoothing the amplified modulation signal output from the amplifier circuit 550 to output the generated drive signal COMA from the drive signal output circuit 51a. The smoothing circuit 560 includes a coil L1 and a capacitor C1.

The amplified modulation signal output from the amplifier circuit 550 is input to one end of the coil L1. The other end of the coil L1 is coupled to the terminal Out serving as an output of the drive signal output circuit 51a. That is, the drive signal output circuit 51a is coupled to each of the selection circuits 230 via the terminal Out. As a result, the drive signal COMA output from the drive signal output circuit 51a is supplied to the selection circuit 230. The other

end of the coil L1 is also coupled to one end of the capacitor C1. The ground potential is supplied to the other end of the capacitor C1. That is, the coil L1 and the capacitor C1 demodulates the amplified modulation signal by smoothing the amplified modulation signal output from the amplifier circuit 550, and output the demodulated signal as the drive signal COMA.

The first feedback circuit 570 includes a resistor R3 and a resistor R4. One end of the resistor R3 is coupled to the terminal COMA-Out through which the drive signal COMA is output, and the other end is coupled to the terminal Vfb and one end of the resistor R4. The voltage VHV is supplied to the other end of the resistor R4. As a result, the drive signal COMA that has passed through the first feedback circuit 570 from the terminal Out is fed back to the terminal Vfb in a pulled-up state.

The second feedback circuit 572 includes capacitors C2, C3, and C4 and resistors R5 and R6. One end of the capacitor C2 is coupled to the terminal Out through which the drive signal COMA is output, and the other end is coupled to one end of the resistor R5 and one end of the resistor R6. The ground potential is supplied to the other end of the resistor R5. Thus, the capacitor C2 and the resistor R5 function as a high pass filter. The cut-off frequency of the high-pass filter is set to, for example, about 9 MHz. The other end of the resistor R6 is coupled to one end of the capacitor C4 and one end of the capacitor C3. The ground potential is supplied to the other end of the capacitor C3. Thus, the resistor R6 and the capacitor C3 function as a low pass filter. The cutoff frequency of the LPF is set to, for example, about 160 MHz. In this way, since the second feedback circuit 572 includes the high-pass filter and the low-pass filter, so that the second feedback circuit 572 functions as a band pass filter that passes a predetermined frequency range of the drive signal COMA.

The other end of the capacitor C4 is coupled to the terminal Ifb of the integrated circuit 500. As a result, a signal obtained by cutting the DC component out of the high frequency components of the drive signal COMA that has passed through the second feedback circuit 572 that functions as the band pass filter is fed back to the terminal Ifb.

The drive signal COMA output from the terminal Out is a signal obtained by smoothing the amplified modulation signal by the smoothing circuit 560. The drive signal COMA is integrated/subtracted via the terminal Vfb, and then fed back to the adder 512. Therefore, the drive signal output circuit 51a self-oscillates at a frequency determined by the feedback delay and the feedback transfer function.

However, since the feedback path via the terminal Vfb has a large delay amount, so that there is a case where the frequency of the self-oscillation cannot be made high enough to ensure the accuracy of the drive signal COMA simply by the feedback via the terminal Vfb. Therefore, the delay in the entire circuit is reduced by providing a path for feeding back the high-frequency component of the drive signal COMA via the terminal Ifb separately from the path via the terminal Vfb. As a result, the frequency of the voltage signal As can be made high enough to ensure the accuracy of the drive signal COMA as compared with the case where there is no path via the terminal Ifb.

FIG. 11 is a diagram illustrating the waveforms of the voltage signal As and the modulation signal Ms in association with the waveform of the analog base drive signal aA.

As shown in FIG. 11, the voltage signal As is a triangular wave, and its oscillation frequency varies according to the voltage of the base drive signal aA. Specifically, the frequency is highest when the voltage of the base drive signal

aA has an intermediate value, and decreases as the voltage of the base drive signal aA has a value higher or lower than the intermediate value.

Further, the slope of the triangular wave of the voltage signal As at the rise of the voltage is almost equal to that at the fall of the voltage when the voltage has the nearly intermediate value. Therefore, the duty ratio of the modulation signal Ms obtained by comparing the voltage signal As with the thresholds Vth1 and Vth2 of the comparator 514 is approximately 50%. When the voltage of the base drive signal aA increases from the intermediate value, the downward slope of the voltage signal As is gentle. Therefore, the period during which the modulation signal Ms is at H level is relatively long, and the duty ratio of the modulation signal Ms increases. On the other hand, when the voltage of the base drive signal aA decreases from the intermediate value, the upward slope of the voltage signal As decreases. Therefore, the period during which the modulation signal Ms is at H level is relatively short, and the duty ratio of the modulation signal Ms decreases.

The gate driver 521 turns on or off the transistor M1 based on the modulation signal Ms. That is, the gate driver 521 turns on the transistor M1 when the modulation signal Ms is at H level, and turns off the transistor M1 when the modulation signal Ms is at L level. The gate driver 522 turns on or off the transistor M2 based on the logically inverted signal of the modulation signal Ms. That is, the gate driver 522 turns off the transistor M2 when the modulation signal Ms is at H level and turns on the transistor M2 when the modulation signal Ms is at L level.

Therefore, the voltage value of the drive signal COMA obtained by smoothing the amplified modulation signal output from the amplifier circuit 550 by the smoothing circuit 560 increases as the duty ratio of the modulation signal Ms increases, and decreases as the duty ratio decreases. That is, the control is performed so that the waveform of the drive signal COMA matches the waveform obtained by enlarging the voltage of the base drive signal aA obtained by performing the analog conversion on the digital base drive signal dA.

Further, since the drive signal output circuit 51a uses the pulse density modulation, there is also an advantage that the change width of the duty ratio can be made large as compared with that of the pulse width modulation with a fixed modulation frequency. The minimum positive pulse width and the minimum negative pulse width that can be used in the drive signal output circuit 51a are limited by circuit characteristics. Therefore, in the pulse width modulation in which the frequency is fixed, the change width of the duty ratio is limited within a predetermined range. In contrast, with the pulse density modulation, as the voltage of the voltage signal As moves away from the intermediate value, the oscillation frequency decreases, and as a result, it is possible to further increase the duty ratio in a region where the voltage is high. Further, it is possible to further decrease the duty ratio in a region where the voltage is low. Therefore, it is possible to secure a wider range of the change width of the duty ratio by employing self-oscillation type pulse density modulation.

1.6 Configurations of Drive Circuit Substrate and Drive Signal Output Circuit Substrate

Next, with reference to FIGS. 12 to 15, configurations of a drive signal output circuit substrate 40a on which the drive signal output circuit 51a that outputs the drive signal COMA is mounted, a drive signal output circuit substrate 40b on which the drive signal output circuit 51b that outputs the drive signal COMB is mounted, and

a drive circuit substrate 30 to which the drive signal output circuit substrates 40a and 40b are detachably coupled will be described.

FIG. 12 is a plan view illustrating the configuration of the drive circuit substrate 30. As shown in FIG. 12, the drive circuit substrate 30 includes a substrate 300 and connectors 310, 320, 330a and 330b.

The substrate 300 has a substantially rectangular shape including a side 301, a side 302 facing the side 301, a side 303 intersecting the side 301 and the side 302, and a side 304 that faces the side 303, and that intersects the side 301 and the side 302.

The substrate 300 is provided with connectors 310, 320, 330a and 330b. Various signals including the clock signal SCK, the print data signal SI, the latch signal LAT, the change signal CH, and the base drive signals dA and dB are input to the connector 310 from the control circuit 100 provided outside the drive circuit substrate 30. That is, the connector 310 is electrically coupled to the control circuit 100 and the control unit 10 including the control circuit 100.

The drive signals COMA and COMB output from the drive signal output circuits 51a and 51b mounted on the drive signal output circuit substrates 40a and 40b are input to the connector 320. Further, the clock signal SCK, the print data signal SI, the latch signal LAT, and the change signal CH that have propagated through the substrate 300 are input to the connector 320. Then, the various signals including the drive signals COMA and COMB, the clock signal SCK, the print data signal SI, the latch signal LAT, and the change signal CH are input to the print head 20. That is, the connector 320 is electrically coupled to the print head 20. The connector 320 or a terminal (not shown) included in the connector 320 is an example of a coupling terminal, and the substrate 300 on which the connector 320 is provided is an example of a first substrate.

The drive signal output circuit substrate 40a is electrically coupled to the drive circuit substrate 30 via the connector 330a and is fixed to the drive circuit substrate 30 by screws 341a and 342a. Similarly, the drive signal output circuit substrate 40b is electrically coupled to the drive circuit substrate 30 via the connector 330b and is fixed to the drive circuit substrate 30 by screws 341a and 342a.

Here, the drive circuit substrate 30 electrically coupled to the print head 20 is an example of a first circuit substrate, and at least one of the drive signal output circuit substrates 40a and 40b electrically coupled to the drive circuit substrate 30 is an example of a second circuit substrate.

FIG. 13 is a plan view illustrating the configuration of the drive signal output circuit substrates 40a and 40b. Here, the drive signal output circuit substrates 40a and 40b have the same configuration, and when the drive signal output circuit substrates 40a and 40b do not need to be particularly distinguished, they are simply referred to as a drive signal output circuit substrate 40. The drive signal output circuits 51a and 51b mounted on the drive signal output circuit substrate 40 are referred to as a drive signal output circuit 51, and the drive signals COMA and COMB output by the drive signal output circuit 51 are referred to as a drive signal COM.

The drive signal output circuit substrate 40 includes the drive signal output circuit 51 that outputs the drive signal COM for driving the piezoelectric element 60, a plurality of terminals 410 through which the base drive signal dA or the base drive signal dB, which is the basis of the drive signal COM, is input to the drive signal output circuit 51, and a substrate 400 on which the drive signal output circuit 51 and the plurality of terminals 410 are provided.

The substrate 400 has a substantially rectangular shape including a side 401, a side 402 facing the side 401, a side 403 that intersects the side 401 and the side 402, and a side 404 that faces the side 403, and that intersects the side 401 and the side 402. Then, as shown in FIG. 13, the side 401 and the side 402 of the substrate 400 are longer than the side 403 and the side 404. In other words, the substrate 400 includes the side 403 and the side 404, and the side 401 and the side 402 longer than the side 403 and the side 404. Here, the substrate 400 is an example of the second substrate.

The plurality of terminals 410 provided on the substrate 400 is located side by side in the direction along the side 403 of the substrate 400. The plurality of terminals 410 is electrically coupled to the connector 330a or the connector 330b included in the drive circuit substrate 30. The base drive signals dA and dB are input to the drive signal output circuit substrate 40 via the plurality of terminals 410. Here, the terminal 410 is an example of an input terminal, and at least one of the base drive signals dA and dB is an example of a first base drive signal.

The drive signal output circuit 51 is located toward the side 404 of the substrate 400 relative to the plurality of terminals 410 located side by side in the direction along the side 403. In other words, at least one of the plurality of terminals 410 and the drive signal output circuit 51 are located side by side in the direction along the side 401.

As shown in FIG. 10, the drive signal output circuit 51 includes the integrated circuit 500, the output circuit 580, the first feedback circuit 570, and the second feedback circuit 572. The integrated circuit 500 and the output circuit 580 are located toward the side 404 of the substrate 400 relative to the plurality of terminals 410 and are located side by side in the order of the integrated circuit 500 and the output circuit 580 along the direction from the side 403 to the side 404. In other words, the integrated circuit 500 and the output circuit 580 are located side by side in the direction along the side 401. In addition, the first feedback circuit 570 and the second feedback circuit 572 are located toward the side 404 of the substrate 400 relative to the plurality of terminals 410, and are located toward the side 401 relative to the integrated circuits 500 and the output circuit 580 located side by side in the direction along the side 401. Further, the integrated circuit 500 includes the reference voltage generation circuit 530 that outputs the reference voltage signal VBS as described above. That is, the reference voltage generation circuit 530 is also provided on the substrate 400.

In addition, the substrate 400 has insertion holes 441 and 442. The insertion holes 441 and 442 are located toward the side 404 relative to the drive signal output circuit 51, and are provided in the direction along the side 404 in the order of the insertion hole 441 and the insertion hole 442 along the direction from the side 401 to the side 402. The screw 341a or the screw 341b is inserted into the insertion hole 441. The screw 342a or the screw 342b is inserted into the insertion hole 442. Then, each of the screws 341a, 341b, 342a, and 342b is fastened to the drive circuit substrate 30, so that the drive signal output circuit substrate 40 is fixed to the drive circuit substrate 30. Here, at least one of the screws 341a and 341b that fixes the drive signal output circuit substrate 40 to the drive circuit substrate 30 is an example of a first fixing portion, and at least one of the screws 342a and 342b that fixes the drive signal output circuit substrate 40 to the drive circuit substrate 30 is an example of a second fixing portion.

Next, the coupling between the drive circuit substrate 30 and the drive signal output circuit substrates 40a and 40b will be described with reference to FIGS. 12 to 15. FIG. 14 is a diagram illustrating a cross section taken along line

XIV-XIV of FIG. 12, and FIG. 15 is a diagram illustrating a cross section taken along line XV-XV of FIG. 12.

As shown in FIGS. 12 to 15, the drive circuit substrate 30 and the drive signal output circuit substrates 40a and 40b are provided such that when viewed from a direction orthogonal to a face 305 which is one face of the substrate 300, at least part of the face 305 which is one face of the substrate 300 and a face 406 which is one face of the substrate 400 overlap with each other. That is, the drive circuit substrate 30 and the drive signal output circuit substrates 40a and 40b are located such that at least part of the face 305 of the substrate 300 and the face 406 of the substrate 400 face each other.

As shown in FIG. 15, in the drive signal output circuit substrate 40a, a portion, of the substrate 400 toward the side 403, where the plurality of terminals 410 is located is inserted into the connector 330a. The connector 330a includes a plurality of conductive portions 331a. The portion of the substrate 400 toward the side 401 included in the drive signal output circuit substrate 40 is inserted into the connector 330a, whereby each of the plurality of conductive portions 331a included in the connector 330a and each of the plurality of terminals 410 provided on the substrate 400 are electrically coupled.

The conductive portion 331a included in the connector 330a is electrically coupled to propagation wiring 350a provided on the face 305 of the substrate 300 included in the drive circuit substrate 30. As a result, various signals including the base drive signal dA propagating through the drive circuit substrate 30 are input to the drive signal output circuit substrate 40a.

The base drive signal dA input to the drive signal output circuit substrate 40a propagates through propagation wiring (not shown) provided on the substrate 400 and is input to the drive signal output circuit 51a. Then, the drive signal output circuit 51a outputs the drive signal COMA based on the input base drive signal dA. The drive signal COMA output from the drive signal output circuit 51a propagates through propagation wiring 451a provided around the insertion hole 441. The propagation wiring 451a is electrically coupled to the screw 341a by inserting the screw 341a into the insertion hole 441.

Further, the screw 341a inserted through the insertion hole 441 is inserted through a spacer 591a and an insertion hole 345a of the substrate 300, and is tightened by a nut 343a provided toward a face 306 of the substrate 300. As a result, the drive signal output circuit substrate 40a is fixed to the drive circuit substrate 30. Further, the screw 341a is tightened with the nut 343a, so that the nut 343a is electrically coupled to propagation wiring 351a provided on the face 306 of the substrate 300. That is, the drive signal COMA is output to the drive circuit substrate 30 via the propagation wiring 451a, the screw 341a, and the nut 343a. In other words, the screw 341a also serves as an output terminal through which the drive signal COMA is output to the drive circuit substrate 30. Here, the screw 341a through which the drive signal COMA is output is an example of a first output terminal. The configuration including the insertion hole 441 and the propagation wiring 451a is an example of a first fixing member mounting unit.

Further, as described above, the drive signal output circuit 51a provided on the drive signal output circuit substrate 40a also outputs the reference voltage signal VBS. As shown in FIG. 15, the reference voltage signal VBS output from the drive signal output circuit 51a propagates through propagation wiring 452a provided around the insertion hole 442.

The propagation wiring **452a** is electrically coupled to the screw **342a** by inserting the screw **342a** into the insertion hole **442**.

Further, the screw **342a** inserted through the insertion hole **442** is inserted through a spacer **592a** and an insertion hole **346a** of the substrate **300**, and is tightened by a nut **344a** provided toward the face **306** of the substrate **300**. As a result, the drive signal output circuit substrate **40a** is fixed to the drive circuit substrate **30**. Further, the screw **342a** is tightened with the nut **344a**, so that the nut **344a** is electrically coupled to the propagation wiring **352a** provided on the face **306** of the substrate **300**. That is, the reference voltage signal VBS is output to the drive circuit substrate **30** via the propagation wiring **452a**, the screw **342a**, and the nut **344a**. In other words, the screw **342a** also serves as an output terminal through which the reference voltage signal VBS is output to the drive circuit substrate **30**. Here, the screw **342a** through which the reference voltage signal VBS is output is an example of a second output terminal.

Here, the coupling between the drive signal output circuit substrate **40b** on which the drive signal output circuit **51b** that generates the drive signal COMB is mounted and the drive circuit substrate **30** is the same as the coupling between the drive signal output circuit substrate **40a** and the drive circuit substrate **30**. Therefore, the base drive signal dB is input to the drive signal output circuit substrate **40b** via the plurality of terminals **410**, and the drive signal output circuit **51b** included in the drive signal output circuit substrate **40b** outputs the reference voltage signal VBS based on the base drive signal dB, while outputting the drive signal COMB. The drive signal COMB output from the drive signal output circuit **51b** is output to the drive circuit substrate **30** with the screw **341b** as an output terminal, and the reference voltage signal VBS is output to the drive circuit substrate **30** with the screw **342b** as an output terminal. That is, the screw **341b** also serves as an output terminal through which the drive signal COMB is output to the drive circuit substrate **30**, and the screw **342b** also serves as an output terminal through which the reference voltage signal VBS is output to the drive circuit substrate **30**.

Here, as shown in FIGS. 13 to 15, the drive signal output circuit **51a** is located between the plurality of terminals **410** and the screws **341a** and **342a**. Therefore, in the drive signal output circuit substrate **40a**, the base drive signal dA is input to the drive signal output circuit **51a** from the plurality of terminals **410** provided along the side **403** of the substrate **400**, and the drive signal COMA generated by the drive signal output circuit **51a** and the reference voltage signal VBS are output from the screws **341a** and **342a** provided toward the side **404** of the substrate **400**. That is, in the drive signal output circuit substrate **40a**, various signals propagate from the side **403** to the side **404**.

Similarly, the drive signal output circuit **51b** is located between the plurality of terminals **410** and the screws **341b** and **342b**. Therefore, in the drive signal output circuit substrate **40b**, the base drive signal dB is input to the drive signal output circuit **51b** from the plurality of terminals **410** provided along the side **403** of the substrate **400**, and the drive signal COMB generated by the drive signal output circuit **51b** and the reference voltage signal VBS are output from the screws **341b** and **342b** provided toward the side **404** of the substrate **400**. That is, in the drive signal output circuit substrate **40b**, various signals propagate from the side **403** to the side **404**.

The drive signal output circuit substrates **40a** and **40b** are configured as described above, so that it is possible to reduce

the possibility that the routing of the propagation wiring provided on the substrate **400** is complicated.

Here, the drive signal output circuit substrate **40** corresponds to the circuit substrate in the present embodiment.

5 1.7 Functions and Effects

As described above, in the liquid ejecting apparatus **1** according to the embodiment, the drive signal output circuit substrates **40a** and **40b** are fixed to the drive circuit substrate **30** with the screws **341a** and **341b**. In this case, the drive signal COMA output from the drive signal output circuit substrate **40a** included in the drive signal output circuit substrate **40a** is output to the drive circuit substrate **30** via the screw **341a**, and the drive signal COMB output from the drive signal output circuit substrate **40b** is output to the drive circuit substrate **30** via the screw **341b**. That is, the screws **341a** and **341b** that fixes the drive signal output circuit substrates **40a** and **40b** to the drive circuit substrate **30** also serve as output terminals through which the drive signals COMA and COMB are output. As a result, it is not necessary to separately provide, on the drive signal output circuit substrates **40a** and **40b**, terminals and connectors through which the drive signals COMA and COMB having large voltage values are output. Therefore, it is possible to reduce the area occupied by the terminals and the connectors through which signals are input and output to and from the drive signal output circuit substrates **40a** and **40b** in the drive signal output circuit substrates **40a** and **40b**.

30 2. Second Embodiment

Next, the liquid ejecting apparatus **1** according to the second embodiment will be described. In the description of the liquid ejecting apparatus **1** according to the second embodiment, the same components as those in the first embodiment will be denoted by the same reference numerals, and the description thereof may be omitted or simplified.

FIG. 16 is a plan view illustrating the configuration of the drive circuit substrate **30** in the second embodiment. FIG. 17 is a plan view illustrating the configuration of the drive signal output circuit substrate **40** in the second embodiment. As shown in FIGS. 16 and 17, the liquid ejecting apparatus **1** according to the second embodiment is different from the liquid ejecting apparatus **1** in the first embodiment in that the drive signal output circuits **51a** and **51b** are mounted on one drive signal output circuit substrate **40**.

As shown in FIG. 16, the drive circuit substrate **30** includes the substrate **300** and the connectors **310**, **320**, and **330**.

50 The substrate **300** has a substantially rectangular shape including the side **301**, the side **302** facing the side **301**, the side **303** intersecting the side **301** and the side **302**, and the side **304** that faces the side **303**, and that intersects the side **301** and the side **302**. The substrate **300** is provided with the connectors **310**, **320**, and **330**.

As in the liquid ejecting apparatus **1** in the first embodiment, the connector **310** is electrically coupled to the control circuit **100** and the control unit **10** including the control circuit **100**. Further, as in the liquid ejecting apparatus **1** according to the first embodiment, the connector **320** is electrically coupled to the print head **20**. Further, the connector **320** is electrically coupled to the drive signal output circuit substrate **40**. The drive signal output circuit substrate **40** is fixed to the drive circuit substrate **30** with screws **341**, **342**, and **343**.

Here, the drive circuit substrate **30** electrically coupled to the print head **20** is an example of the first circuit substrate

in the second embodiment, and the drive signal output circuit substrate **40** electrically coupled to the drive circuit substrate **30** is an example of the second circuit substrate. Further, the substrate **300** on which the connector **320** is provided is an example of the first substrate in the second embodiment.

As shown in FIG. 17, the drive signal output circuit substrate **40** in the second embodiment includes the drive signal output circuit **51a** that outputs the drive signal COMA for driving the piezoelectric element **60**, the drive signal output circuit **51b** that outputs the drive signal COMB for driving the piezoelectric element **60**, the plurality of terminals **410** through which the base drive signal **dA** that is the basis of the drive signal COMA and the base drive signal **dB** that is the basis of the drive signal COMB are input, and the substrate **400** on which the drive signal output circuit **51** and the plurality of terminals **410** are provided.

Here, the drive signal COMA is an example of the first drive signal in the second embodiment, and the drive signal COMB is an example of the second drive signal in the second embodiment. The drive signal output circuit **51a** that outputs the first drive signal is an example of the first drive signal output circuit in the second embodiment, and the drive signal output circuit **51b** that outputs the second drive signal is an example of the second drive signal output circuit in the second embodiment.

As shown in FIG. 17, the substrate **400** has a substantially rectangular shape including the side **401**, the side **402** facing the side **401**, the side **403** that intersects the side **401** and the side **402**, and the side **404** that faces the side **403**, and that intersects the side **401** and the side **402**. The side **401** and the side **402** of the substrate **400** are longer than the side **403** and the side **404**. In other words, the substrate **400** includes the side **403** and the side **404**, and the side **401** and the side **402** longer than the side **403** and the side **404**.

Here, the substrate **400** is an example of the second substrate in the second embodiment, at least one of the side **403** and the side **404** is an example of the first side in the second embodiment, and at least one of the side **401** and the side **402** is an example of the second side in the second embodiment.

The plurality of terminals **410** provided on the substrate **400** is located side by side in the direction along the side **403** of the substrate **400**. The plurality of terminals **410** is electrically coupled to the connector **330** included in the drive circuit substrate **30**. The base drive signals **dA** and **dB** are input to the drive signal output circuit substrate **40** via the plurality of terminals **410**. Here, the terminal **410** is an example of the input terminal in the second embodiment, and the base drive signal **dA** is an example of the first base drive signal in the second embodiment.

The drive signal output circuit **51a** is located toward the side **404** of the substrate **400** relative to the plurality of terminals **410** located side by side in the direction along the side **403**. Further, the drive signal output circuit **51b** is located toward the side **404** of the substrate **400** relative to the drive signal output circuit. In other words, the drive signal output circuit **51a** and the drive signal output circuit **51b** are located side by side in the direction along the side **401**.

Further, the substrate **400** has insertion holes **441**, **442**, and **443**. The insertion holes **441**, **442**, and **443** are located toward the side **404** relative to the drive signal output circuit **51b**, and are provided in the direction along the side **404** in the order of the insertion hole **441**, the insertion hole **442**, and the insertion hole **443** along the direction from the side **401** to the side **402**. Then, the screw **341** is inserted through

the insertion hole **441**, the screw **342** is inserted through the insertion hole **442**, and the screw **343** is inserted through the insertion hole **443**.

Each of the screws **341**, **342**, and **343** is fastened to the drive circuit substrate **30**, so that the drive signal output circuit substrate **40** is fixed to the drive circuit substrate **30**. Here, the screw **341** that fixes the drive signal output circuit substrate **40** to the drive circuit substrate **30** is an example of the first fixing portion in the second embodiment, the screw **342** that fixes the drive signal output circuit substrate **40** to the drive circuit substrate **30** is an example of the second fixing portion in the second embodiment, and the screw **342** that fixes the drive signal output circuit substrate **40** to the drive circuit substrate **30** is an example of the third fixing portion in the second embodiment.

Further, as in the screws **341a**, **341b**, **342a**, and **342b** of the first embodiment, each of the screws **341**, **342**, and **343** also serves as an output terminal through which the signal generated by the drive signal output circuit substrate **40** is output to the drive circuit substrate **30**.

Specifically, the screw **341** also serves as an output terminal through which the drive signal COMA is output to a fixing member that fixes the drive signal output circuit substrate **40** to the drive circuit substrate **30** and the drive circuit substrate **30**, the screw **342** also serves as an output terminal through which the reference voltage signal **VBS** is output to a fixing member that fixes the drive signal output circuit substrate **40** to the drive circuit substrate **30** and the drive circuit substrate **30**, and the screw **343** also serves as an output terminal through which the drive signal COMB is output to a fixing member that fixes the drive signal output circuit substrate **40** to the drive circuit substrate **30** and the drive circuit substrate **30**.

Even the liquid ejecting apparatus **1** of the second embodiment configured as described above can achieve the same functions and effects as the liquid ejecting apparatus **1** of the first embodiment. Here, the screw **341** through which the drive signal COMA is output is an example of the first output terminal in the second embodiment, the screw **342** through which the reference voltage signal **VBS** is output is an example of the second output terminal in the second embodiment, and the screw **343** through which the drive signal COMB is output is an example of the third output terminal in the second embodiment.

Also, as shown in FIGS. 16 and 17, in the drive circuit substrate **30** and the drive signal output circuit substrate **40**, the screw **342** through which the reference voltage signal **VBS** is output is preferably located between the screw **341** through which the drive signal COMA is output and the screw **343** through which the drive signal COMB is output.

The drive signal **VOUT** generated by selecting or deselecting the drive signals COMA and COMB is supplied to the electrode **611** of the piezoelectric element **60**, and the reference voltage signal **VBS** is supplied to the electrode **612** of the piezoelectric element **60**. For this reason, when the drive signal **VOUT** based on the drive signal COMA is supplied to the piezoelectric element **60**, and when the drive signal **VOUT** based on the drive signal COMB is supplied to the piezoelectric element **60**, a current flowing through the screw **341** and a current in a direction opposite a direction of the current flowing through the screw **343** flow through the screw **342**.

When the screw **342** through which the reference voltage signal **VBS** is output is located between the screw **341** through which the drive signal COMA is output and the screw **343** through which the drive signal COMB is output, a current in a direction opposite a direction of the current

25

flowing through the adjacent screw 341 and screw 343 flows through the screw 342, so that the respective magnetic fields generated by the currents flowing through the screws 341, 342, and 343 are canceled out. As a result, the possibility of mutual interference between the drive signals COMA and COMB and the reference voltage signal VBS is reduced, and the accuracy of the drive signals COMA and COMB and the reference voltage signal VBS can be improved.

3. Modification

In the liquid ejecting apparatus 1 according to the first embodiment and the second embodiment described above, description is made in which the method of fixing the drive signal output circuit substrate 40a, 40b, 40 to the drive circuit substrate 30 includes using the screw, but the method is not limited to this. That is, the method of fixing the drive signal output circuit substrates 40a, 40b, 40 to the drive circuit substrate 30 may include using a conductive member that can fix the drive signal output circuit substrates 40a, 40b, 40 to the drive circuit substrate 30, and for example, may include using a leaf spring.

Although the embodiments and the modification have been described above, the present disclosure is not limited to the embodiments and the modification, and can be implemented in various modes without departing from the gist of the disclosure. For example, the respective embodiments can be combined appropriately.

The disclosure includes a configuration substantially same as the configuration described in the embodiments (for example, a configuration having the same function, method, and result, or a configuration having the same object and effect). Further, the disclosure includes a configuration in which a non-essential part of the configuration described in the embodiments is replaced. Further, the disclosure includes a configuration having the same functions and effects as the configuration described in the embodiments or a configuration capable of achieving the same object. The disclosure also includes a configuration in which a known technique is added to the configuration described in the embodiments.

What is claimed is:

1. A liquid ejecting apparatus comprising: a print head including a drive element, the print head ejecting a liquid by driving the drive element; a first circuit substrate electrically coupled to the print head; a second circuit substrate electrically coupled to the first circuit substrate; and a first fixing portion that fixes the second circuit substrate to the first circuit substrate, wherein the first circuit substrate includes a coupling terminal electrically coupled to the print head, and a first substrate on which the coupling terminal is provided, wherein the second circuit substrate includes a first drive signal output circuit that outputs a first drive signal for driving the drive element, an input terminal that is electrically coupled to the first circuit substrate, and through which a first base drive signal which is a basis of the first drive signal is input to the first drive signal output circuit, and a second substrate on which the first drive signal output circuit and the input terminal are provided, and a reference voltage signal output circuit that outputs a reference voltage signal; and

5

a second fixing portion that fixes the second circuit substrate to the first circuit substrate, wherein the first fixing portion also serves as a first output terminal through which the first drive signal is output to the first circuit substrate, the drive element is a piezoelectric element, and is driven based on a first electrode to which the first drive signal is supplied and a second electrode to which the reference voltage signal is supplied, the reference voltage signal output circuit is provided on the second substrate, and the second fixing portion also serves as a second output terminal through which the reference voltage signal is output to the first circuit substrate.

2. The liquid ejecting apparatus according to claim 1, wherein

the first drive signal output circuit is located between the first fixing portion and the input terminal.

3. The liquid ejecting apparatus according to claim 1, wherein

when viewed from a direction orthogonal to one face of the first substrate, the first circuit substrate and the second circuit substrate are disposed so that at least part of one face of the first substrate and one face of the second substrate overlap each other.

4. The liquid ejecting apparatus of claim 1, further comprising:

a second drive signal output circuit that outputs a second drive signal for driving the drive element; and a third fixing portion that fixes the second circuit substrate to the first circuit substrate, wherein the second drive signal output circuit is provided on the second substrate, and the third fixing portion also serves as a third output terminal through which the second drive signal is output to the first circuit substrate, and wherein the second fixing portion is located between the first fixing portion and the third fixing portion.

5. A drive circuit comprising:

a first circuit substrate; a second circuit substrate electrically coupled to the first circuit substrate; and a first fixing portion that fixes the second circuit substrate to the first circuit substrate, wherein the second circuit substrate includes a first drive signal output circuit that outputs a first drive signal for driving a drive element, an input terminal that is electrically coupled to the first circuit substrate, and through which a first base drive signal which is a basis of the first drive signal is input to the first drive signal output circuit, and a second substrate on which the first drive signal output circuit and the input terminal are provided, and a reference voltage signal output circuit that outputs a reference voltage signal; and a second fixing portion that fixes the second circuit substrate to the first circuit substrate, wherein the first fixing portion also serves as a first output terminal through which the first drive signal is output to the first circuit substrate, the drive element is a piezoelectric element, and is driven based on a first electrode to which the first drive signal is supplied and a second electrode to which the reference voltage signal is supplied, the reference voltage signal output circuit is provided on the second substrate, and wherein

26

the second fixing portion also serves as a second output terminal through which the reference voltage signal is output to the first circuit substrate.

6. A circuit substrate electrically coupled to a first substrate, the circuit substrate comprising:
- a first drive signal output circuit that outputs a first drive signal for driving a drive element;
  - an input terminal that is electrically coupled to the first drive signal output circuit, and through which a first base drive signal which is a basis of the first drive signal is input to the first drive signal output circuit;
  - a first fixing member mounting unit having a first fixing portion fixed to the first substrate;
  - a second substrate on which the first drive signal output circuit, the input terminal, and the first fixing member mounting unit are provided;
  - a reference voltage signal output circuit that outputs a reference voltage signal; and
  - a second fixing portion that fixes the circuit substrate to the first circuit substrate, wherein
- the first fixing member mounting unit also serves as a first output terminal through which the first drive signal is output.
